UNITED STATES PATENT OFFICE.

GEORGE J. HAGAN, OF PITTSBURGH, PENNSYLVANIA.

ANNEALING-FURNACE.

1,083,443.

Specification of Letters Patent.

Patented Jan. 6, 1914.

Application filed September 15, 1913. Serial No. 789,814.

To all whom it may concern:

Be it known that I, GEORGE J. HAGAN, residing at Pittsburgh, in the county of Allegheny and State of Pennsylvania, a citizen 5 of the United States, have invented or discovered certain new and useful Improvements in Annealing-Furnaces, of which improvements the following is a specification.

The invention described herein relates to 10 certain improvements in furnaces for malleableizing castings, and has for its object a construction permitting of the use of solid fuel and also permitting of the removal of the treated castings from the annealing box 15 by an electro-magnet.

The invention is hereinafter more fully described and claimed.

In the accompanying drawings forming a 20 part of this specification, Figure 1 is a sectional elevation longitudinal of the furnace; Fig. 2 is a sectional plan on a plane indicated by the line II—II Fig. 1, and Figs. 3 and 4 are sectional elevations transverse of the furnace the planes of section being indicated by the lines III—III and IV—IV Fig. 1.

In the practice of my invention a flue 1 is formed in the foundation or lower portion 25 of the furnace structure and fire chambers 2 are arranged at one or both ends of this flue dependent upon the length of the furnace. The products of combustion escape from the top of this flue through passages 3 extending in opposite directions horizontally 30 the tops of said passages being formed by the bottom of the annealing chamber A as shown in Figs. 1, 3 and 4. At their outer ends these passages discharge into the spaces or narrow chambers 4 formed be-

40 tween the side walls 5^a of the annealing chamber and the outer side walls 5 of the furnace. Baffle plates 6 are arranged approximately half way the height of the chambers 4 and extend from the ends of the 45 latter toward the middle of these chambers as shown in Figs. 1 and 2. As these chambers are uninterrupted except for occasional spacing and tying bricks to support the side walls 5^a of the annealing chamber, 50 the products of combustion flow freely along these chambers toward the ports 7 between the inner ends of the baffle plates 6 and into the chamber 4^a above the baffle wall 6.

55 Narrow spaces or chambers 8 and 8^a are

formed between the end walls 9^a of the annealing chamber and the end walls 9 of the furnace, said chambers being separated one from the other by baffle-walls 10 extending from the side walls of the furnace toward the middle of the chambers at the ends of the annealing chamber, as shown in Figs. 2, 3 and 4. The lower outer corners of the lower end chambers 8 are connected by flues 11 to stack flues 12. As the upper side 60 chambers 4^a connect with the upper end chambers 8^a at the corners of the annealing chamber, the products of combustion as they flow through ports 7 are drawn toward the ends of the chambers 4^a around the corners 65 of the annealing chamber into the upper end chambers 8^a. From these chambers the products of combustion flow down through ports 13 between the inner adjacent ends of the baffles 10 into the lower end chambers 70 75 and separate into two streams and flow into the flues 11 and thence to the stack flues. By reference to Figs. 2 and 3 it will be seen that the lower side chambers 4 are separated from the lower end chambers 8 by 80 walls 18.

It is characteristic of my improved furnace that the products of combustion flow in a plurality of streams into the lower portions of the chambers 4 and converge into 85 one stream midway of the sides of the annealing chamber. After passing through ports 7 the products of combustion separate into two oppositely flowing streams on both sides of the annealing chamber pass around 90 the corners of the latter and flow together at the ports 13, and again separate and flow to the flues 11. Thus the bottom, sides and ends of the annealing chamber will be uniformly heated.

During the annealing operation the open top of the annealing chamber is hermetically sealed by a cover 14 provided around its lower edge with flanges 15, which project down into sand or other suitable material contained in troughs 16 in the top of the wall of the furnace. If the furnace is long the cover is preferably made in sections as shown in Fig. 1, and the strengthening or bracing channels 17 adjacent to the ends of the sections are arranged to form troughs for the reception of sand or other material to seal the joint between sections.

By employing an annealing chamber having an open top, the articles after being an-

nealed can be removed quickly by an electro-magnet, to which the articles will adhere and also to one another.

I claim herein as my invention:

- 5 An annealing furnace, having in combination therewith an open topped annealing chamber so arranged within the outer walls of the furnace as to form spaces at sides and ends of the annealing chamber, horizontal 10 baffles dividing said spaces into upper and lower compartments, said baffles having ports therethrough at the sides and ends of the annealing chamber, a flue extending

under the annealing chamber, passages extending transversely under the bottom of 15 the annealing chamber and connecting said flue with the lower side compartments and outlet flues extending from the lower end compartments to the stack flue.

In testimony whereof, I have hereunto set 20 my hand.

GEORGE J. HAGAN.
